ABSTRACT

Vertebrates can be anesthetized regionally by a subarachnoid administration of tetrodotoxin or desoxytetrodotoxin. The amount of tetrodotoxin which should be administered in a preferred embodiment ranges between 1 and 12 micrograms, whereas the amount of desoxytetrodotoxin ranges between 10 and 120 micrograms.

5 Claims, 1 Drawing Figure

FIG. 1

SPINAL ANESTHESIA USING SMALL AMOUNTS
OF TETRODOTOXIN OR
DESOXYTETRODOTOXIN

The present invention relates to a method of obtaining spinal anesthesia (i.e., by injection of an anesthetic into the subarachnoid space which contains the cerebro-spinal fluid) and a pharmaceutical preparation which can be used with this method.

Toxins from marine sources of extraordinary potency have been known for many years. This invention particularly concerns novel uses for tetrodotoxin, and for its derivative, desoxytetrodotoxin.

Tetrodotoxin is obtained from the ovaries and eggs of several species of puffer fish of the suborder *Gymnodontes*. It is also found in certain species of California newts of the genus *Taricha*; and the toxin obtained from these species, known as tarichatoxin, is identical with tetrodotoxin. Tetrodotoxin has been purified, and its molecular structure is determined to be an amino 20 perhydroquinazoline of the formula:

meability of the connective tissue sheath of peripheral nerves seemed likely to preclude its use as a local anesthetic agent.

Combinations of tetrodotoxin with a local anesthetic 5 compound have been found to possess unusual anesthetic properties. This is manifested most significantly in improved longevity of action of combinations of the toxin with local anesthetics. In these combinations, tetrodotoxin is typically used in concentrations below those which produce reliable nerve blocks. The site of administration of the tetrodotoxin and anesthetic is outside the dura of the spinal canal, i.e., a peridural administration. It is theorized that the local anesthetic enables the tetrodotoxin or desoxytetrodotoxin to penetrate the sheath surrounding the nerve roots and produce local anesthesia.

The present invention relies upon a subarachnoid spinal administration into the intact mammal of a composition which consists essentially of small amounts of tetrodotoxin or desoxytetrodotoxin. In this case, it is not therefore necessary to combine these compounds with

(Zwitterion form)

Tetrodotoxin and species in which it occurs are more fully described in *Pharmacological Reviews*, Vol. 18, No. 2, at pages 997-1049. Some of the effects of tetrodotoxin and its derivatives, e.g., desoxytetrodotoxin, are described in *Chemical Abstracts*, Vol. 37, p. 1770⁷ (1943) and Vol. 69, Column 9494w (1968).

Experiments with isolated nerves have shown that tetrodotoxin behaves in a fundamentally different manner from local anesthetics such as procaine and cocaine. In a voltage-clamped giant axon from the squid or lobster, the latter agents reduce both inward initial sodium current and outward potassium current. With tetrodotoxin, however, inward sodium current can be reduced or even obliterated, while the outward potassium current is totally unaffected. There are few if any other substances in which this unique action has been established.

Tetrodotoxin has not heretofore found any practical use as an anesthetic. While the compound can be used to induce nerve blocks in laboratory animals, the anesthetic dose is slightly below the lethal dose, which has precluded, as a practical matter, the use of the compound as an anesthetic in its own right. M. H. Evans, *Toxicon*, 1968, Vol. 5, pp. 289-294, tested its use topically on peripheral nerve branches and exposed dorsal and ventral spinal roots in anesthetized cats, and found blocks in the latter case but concluded that the imper-

40 a local anesthetic, and it has been found that very low doses of the compounds give a longer duration of anesthesia than is obtainable with the use of certain prior art anesthetics of differing composition. For example, it is possible to administer a very low dose of 1-12 micrograms (μg) of tetrodotoxin or 10-120 micrograms of desoxytetrodotoxin and obtain a spinal block of between 3 and 24 hours in duration. Thus, subarachnoid 45 anesthesia in mammals, including man, is contemplated. In the case of man, it is believed, based on animal tests, that a minimum dose of 1 μg of tetrodotoxin is effective to produce anesthesia. By contrast, subarachnoid administration of tetracaine (at larger doses of 3-20 mg) gives a block of from 1.5 to 3 hours and xylocaine (at much larger doses of 50-150 mg) gives blocks of from 1 to 2 hours. P. C. Lund, *Principles and Practice of Spinal Anesthesia*, pp. 420 and 425, Charles C. Thomas (publisher), 1971. These known spinal anesthetics cause more irritation and have a greater local 50 toxicity than the composition used in the present invention.

55 It has been found that the administration of the compounds used in the present invention should be delivered into the subarachnoid area of the spinal column for effective anesthesia to be induced. A particularly preferred dosage range is from 3 to 6 micrograms of tetrodotoxin and 30 to 60 micrograms of desoxytetrodotoxin.

The active compounds, tetrodotoxin or desoxytetrodotoxin, are preferentially carried by either a hypobaric, an isobaric, or a hyperbaric solution. Hypobaric solutions can be prepared using, e.g., triple distilled water as the vehicle for the drug. Isobaric solutions are usually prepared by using cerebrospinal fluid as the vehicle but sodium chloride added in a suitable concentration to an aqueous solution of the compound can also be used to obtain isobaricity. Hyperbaric solutions can be prepared by addition of varying amounts of glucose (usually 5-10%) to a water solution of the compounds. A hyperbaric solution, the most commonly

procedure to be performed.

The following examples show the invention in practice:

EXAMPLE 1

This example illustrates pharmaceutical compositions and methods for preparing them which are hypobaric solutions containing 1.0, 2.0, 3.0, 4.0, 5.0, 6.0, 8.0, and 10.0 $\mu\text{g}/\text{ml}$ tetrodotoxin hydrochloride; pH 3.5-5.0

The tetrodotoxin hydrochloride is dissolved in a

Concentration $\mu\text{g}/\text{ml}$ Component	1	2	3	4	5	6	8	10
	Amount							
Tetrodotoxin hydrochloride (mg)	10	20	30	40	50	60	80	100
Hydrochloric acid, 2N							If necessary to adjust pH	
Sodium hydroxide, 2N							If necessary to adjust pH	
Water for injection USP XVIII							Sufficient quantity to make 10 liters	

used preparation, can be easily formulated so that the pharmaceutical composition containing the compound used in the present invention can be controlled by gravity within the cerebrospinal fluid, i.e., by tilting the patient head upwards or head downwards from the horizontal plane. The hyperbaric solution enables the anesthesiologist to control the movement of the anesthetic and thereby the extent of anesthesia in a manner that is well known in the art. The acidity of the solutions described above is kept inside limits that give good stability to the tetrodotoxin or desoxytetrodotoxin.

25 small amount of water and is diluted to a volume of 9.5 liters. The pH is adjusted and a sufficient volume of water is added to make a solution of 10 liters which is then sterilized.

EXAMPLE 2

This example illustrates pharmaceutical compositions and methods for preparing them which are isobaric solutions containing 1.0, 2.0, 3.0, 4.0, 5.0, 6.0, 8.0, and 10.0 $\mu\text{g}/\text{ml}$ tetrodotoxin hydrochloride; pH 3.5-5.0.

Concentration $\mu\text{g}/\text{ml}$ Component	1	2	3	4	5	6	8	10
	Amount							
Tetrodotoxin hydrochloride (mg)	10	20	30	40	50	60	80	100
Sodium chloride USP XVII (g)	90	90	90	90	90	90	90	90
Hydrochloric acid, 2N							If necessary to adjust pH	
Sodium hydroxide, 2N							If necessary to adjust pH	
Water for injection USP XVIII							Sufficient quantity to make 10 liters.	

If desired, addition of a vasoconstrictor, e.g. epinephrine, to the pharmaceutical preparation can also be made in manners that are well known in the art. The concentration of active ingredient is generally 1-12 micrograms/ml for tetrodotoxin and 10-120 micrograms/ml of desoxytetrodotoxin and volumes of approximately 1-6 ml of solution are injected into the cerebrospinal fluid contained in the subarachnoid space of the vertebrate to be anesthetized. The type of solution to be used, the concentration and volume to be administered are dependent on such factors as, for instance, age and size of the patient and on the surgical

50 The tetrodotoxin hydrochloride is dissolved in a small amount of water. Sodium chloride is added and water for injection is added to a total volume of about 9.5 liters. After dissolution of the salt the pH is adjusted and thereafter a sufficient volume of water is added to make a solution of 10 liters which is then sterilized.

EXAMPLE 3

This example illustrates pharmaceutical compositions and methods for preparing them, which are hyperbaric solutions containing 1.0, 2.0, 3.0, 4.0, 5.0, 8.0 and 10.0 $\mu\text{g}/\text{ml}$ tetrodotoxin hydrochloride; pH 3.5-5.0.

Concentration $\mu\text{g}/\text{ml}$ Component	1	2	3	4	5	5	8	10
	Amount							
Tetrodotoxin hydrochloride (mg)	10	20	30	40	50	50	80	100
Dextrose, anhydrous USP XVIII (g)	500	500	500	500	500	750	500	500
Hydrochloric acid, 2N							If necessary to adjust pH	
Sodium hydroxide, 2N							If necessary to adjust pH	
Water for injection USP XVIII							Sufficient quantity to make 10 liters	

The tetrodotoxin hydrochloride is dissolved in a small amount of water and diluted to 9.0 liters. The pH is adjusted. The dextrose is added and dissolved. A sufficient volume of water is added to make a solution of 10 liters which is then sterilized.

Other forms of tetrodotoxin such as salts of other acids than hydrochloric acid or such as the base or zwitterion form can be used and solutions can be prepared containing amounts equivalent to those of tetrodotoxin hydrochloride given in Examples 1-3.

In the case of desoxytetrodotoxin, compositions are made in the same manner as shown in Example 1-3 for tetrodotoxin, except that the concentrations of biotoxin are 10 to 100 $\mu\text{g}/\text{ml}$, because desoxytetrodotoxin is about one-tenth as active as tetrodotoxin.

minutes of the injection with recovery occurring before 17, 19.5 and 23 hours had elapsed from the time of the injection, respectively, in the animals. In two animals full recovery occurred within 28 hours, while in the third some ataxia was noted for an additional 12 to 24 hours with full recovery within 48 hours from the time of injection. The spread of the anesthesia towards the head (cephalad spread) was on the average of 4 to 5 segments from the point of injection. Excessive cephalad spread is indicated by signs of Horner's syndrome, head drop, abdominal breathing, cyanosis and front limb paresis. None of these signs were observed. Anesthesia in the lower region of the spinal column (caudal region) was complete. Table I sets forth the results obtained.

EXAMPLE 4

35

EXAMPLE 5

Three sheep weighing between 28 and 29.5 kg and of approximately 4.5 to 5 months of age were treated with tetrodotoxin (3 micrograms). All three sheep were restrained with their lumbar and thoracic spine in horizontal position during the subarachnoid injection, which was made over a period of 5 to 10 seconds using a 22 gauge-3 inch spinal needle at the interspace between the sixth lumbar and first sacral segments. The sheep were then immediately tilted so that the slope of the lumbar and thoracic spine was positioned 10° to the horizontal (caudal inferior).

The response to the tetrodotoxin was a rapid onset of anesthesia (within less than 4 minutes, usually within 2 to 3 minutes), with a long sensory block followed by complete recovery. Although the limitations of the normal working day interfered with exact measurements of the duration of the block, it was determined that the sensory blocks were still present after 190, 320 and 420

The procedure used in Example 4 was employed using a 6 microgram dose of tetrodotoxin. In the three sheep treated with this dose level, the onset of the block was rapid. The blocks lasted for longer than 6.5 hours but less than 24 hours. In one case the block lasted exactly 24 hours. Weight support required 48-72 hours for recovery and complete recovery usually required 72-86 hours. One animal had a persistent slight impairment of one joint that lasted 18 days but which eventually returned to normal. This was due to inflammation from causes other than drug-related causes. Cephalad segmental spread was slightly more exaggerated than the spread observed when animals were treated with 3 micrograms. Regression of two segments required 2-3 hours on the average. The Table given below summarizes the test results:

FIG. 1 is a graph showing the spread and effect of the subarachnoidally administered local anesthetic, versus time after administration.

Using the technique described in the foregoing Examples 4-6, the local anesthetic drug to be tested was injected into the subarachnoid space (which contains the cerebro-spinal fluid), between the six lumbar and the first sacral vertebral interspace of the sheep. Each of three animals received 1.0 ml of 0.25% tetracaine or 0.5% tetracaine or 1.0 ml containing 6 µg of tetrodotoxin. The most commonly used concentration of tetracaine in spinal anesthesia, which is the most commonly used anesthetic in humans, as indicated by Lund (principals and Practice of Spinal Anesthesia, C. C. Thomas Publishers, Springfield, Ill., (1971) p. 420) is 0.25% - 0.3%. Above this concentration the drug becomes increasingly irritating and is not generally used. In man the injection is usually made between either the second and third or third and fourth lumbar interspaces. The drug, after injection, mixes with the spinal fluid and is carried or spread anteriorly and posteriorly.

On the "Y" axis (the ordinate) of FIG. 1 is a schematic representation of the segments of the spinal cord. In the sheep, caudal to cephalad (posterior to anterior) the segments of the spinal cord are: coccygeal 3,2,1; sacral 4,3,2,1; lumbar 6,5,4,3,2,1; thoracic 13,12,11,10,9,8,7,6, 5,4,3,2,1; cervical 7,6,5,4,3,2,1. Thoracic 13 is the only one of the last two groups illustrated or represented in FIG. 1.

Depending on many factors such as concentration, volume of solution, manipulation of the patient and inherent characteristics of the drug, a variable degree of duration and spread of anesthesia can be achieved. This spread and its recovery or so-called regression is pictorially represented as in FIG. 1. Above (or cephalad to) each point there is no anesthesia and the spinal nerves are unaffected by the drug. Below (or caudal to) each point all spinal segments or nerves are blocked. Over a period of time, which is represented on the ab-

30 FIG. 1 therefore represents the level of anesthesia at a particular time and also the total number of spinal segments which are blocked at that time. FIG. 1 compares the level of anesthesia and the segmental regression pattern obtained in sheep after administration of each 35 of the three local anesthetics. Tetracaine, the most commonly used spinal anesthetic in humans, in these experiments anesthetized only a total of 6 or 7 segments and regressed (the animal recovered) completely in between 3-5 hours. Tetrodotoxin, on the other hand, at concentrations far below those of tetracaine blocked a total of between 9-12 segments for at 40 least 6 hours and did not regress completely for about 24 hours.

It is observed from these experiments, as illustrated 45 graphically in FIG. 1, that tetracaine at concentrations of 0.25 and 0.5 percent would provide anesthesia and pain relief in segments below S-3 for only about 3 hours. Tetrodotoxin, however, provided anesthesia and pain relief below S-3 for at least 15 hours.

50 Recovery of function in the animals tested was complete and no sequelae followed the long duration of anesthesia caused by tetrodotoxin.

Upon reading the foregoing description, persons in the art will become aware of a number of modifications 55 that can be made to the invention described herein without the exercise of inventive skill. These modifications are intended to be included within the scope of the invention, and the foregoing is intended to be merely illustrative of certain preferred embodiments of the invention. The appended claims define the scope of protection sought.

We claim:

1. A process for inducing spinal anesthesia in a mammal comprising administration by injection into the 65 subarachnoid space of the intact mammal from about 1 to 6 milliliters of a pharmaceutical composition comprising a compatible vehicle and as the active ingredient a compound selected from the group consisting of

tetrodotoxin in concentration of 1 to 12 micrograms per milliliter and desoxytetrodotoxin in concentration from 10 to 120 micrograms per milliliter of the vehicle.

2. The process as claimed in claim 1 wherein the amount of tetrodotoxin which is administered is from about 1 to 12 micrograms.

3. The process as claimed in claim 1 wherein the amount of desoxytetrodotoxin which is administered is

from 10 to 120 micrograms.

4. The process as claimed in claim 1 wherein the amount of tetrodotoxin which is administered is from about 3 to 6 micrograms.

5. The process as claimed in claim 1 wherein the amount of desoxytetrodotoxin which is administered is from about 30 to 60 micrograms.
